WILLIAM C. MORRILL, OF NEW YORK, N. Y.

APPARATUS FOR DISPENSING LIQUID SOAP.

1,199,913.

Specification of Letters Patent.

Patented Oct. 3, 1916.

Application filed March 23, 1907. Serial No. 364,124.

To all whom it may concern:

Be it known that I, WILLIAM C. MORRILL, a citizen of the United States, residing at the city of New York, borough of Manhattan, and State of New York, have invented a certain new and useful Apparatus for Dispensing Liquid Soap, of which the following is a specification.

This invention is an apparatus for dispensing liquid soap in an economical and hygienic manner, and in regulated quantities as required for use.

There are many objections, both from a sanitary standpoint and otherwise, to using toilet soap in cake form, particularly in places of public resort, such as lavatories, hotels, public buildings, and offices. One ground of such objection is the unsanitary conditions of use arising from the fact that the same cake is used by many different persons, thereby affording great danger, as has been well recognized, for spreading certain contagious diseases. To overcome this disadvantage, most of the better classes of hotels provide their guests with unwrapped "individual" cakes of soap, but this practice, naturally, is very expensive. Furthermore, under conditions of ordinary use in public places, a cake of soap disintegrates and wastes rapidly, and the total outlay required to keep up the supply in a satisfactory manner is a large item of expense. Then again the soap, through careless users, becomes unsightly, and soils the soap-dish and other articles with which it comes in contact.

It has been attempted to overcome the many objections incident to the employment of cake soap, such as by delivering shaved soap, powdered soap or liquid soap from a container, or by using paper or other similar material coated with soap. These various ways, however, particularly as concerns liquid soap, have never gone into any very extended use.

The advantages to be secured from the employment of liquid soap are well known, but to my knowledge no practical system of storing and dispensing such soap has been devised.

Liquid soap always contains volatile solvents, such as alcohol, ammonia, etc., and, also, perfumes, so that a practicable apparatus for dispensing this soap must provide against evaporation of such solvents and perfumes; otherwise very considerable

financial loss results, and further, the liquid soap is deteriorated, lacks uniformity in composition, and the ingredients which separate or crystallize out owing to the evaporation of the solvents clog the container and delivery pipes for the soap. Furthermore if the liquid soap is exposed to the external atmosphere it will become contaminated by dust and other impurities in the atmosphere.

The object of this invention is to keep liquid soap in a condition free from loss of its essential ingredients and in a condition fit for use, and to dispense such soap in regulated quantities with a view to preventing waste thereof, thereby securing economy in the use of the soap, and, also, to overcome the other disadvantages hereinbefore referred to.

In the accompanying drawings, I have illustrated one practical embodiment of the invention, but the construction shown therein is to be understood as illustrative only, and not as defining the limits of the invention.

Figure 1 is an elevation, with the storage tank for the liquid soap in section, of an apparatus for dispensing liquid soap embodying my invention. Fig. 2 is a side elevation of the apparatus shown in Fig. 1. Fig. 3 is a vertical section, partly an elevation, of one form of liquid dispensing and air admitting valve adapted to be used in the present liquid soap dispensing system. Fig. 4 is an elevation, partly in section, illustrating a plurality of throttle-valves which may be used in the distributing pipes of the system. Fig. 5 is an enlarged detail section of the throttle-valve.

A designates a tank for the storage of liquid soap. This tank occupies a position some distance above the wash-stand B, or other form of lavatory to which the liquid soap is to be supplied, but the relation of the storage tank to the wash-stand is a matter of no consequence, except that said tank should be above the lavatory for the purpose of supplying liquid soap by gravity thereto. As shown, the tank A is closed for the purpose of storing the soap free from contact with the external atmosphere, and for preventing dust or dirt from entering the contents thereof, as well as for preventing the volatile ingredients of the soap from evaporating. The tank is shown as having a filling nozzle *a* which is tightly closed by a

- suitable cap *b*. This cap is to be removed only when the tank is to be refilled with the liquid soap, and it is to be understood, therefore, that under normal conditions the cap or closure *b* is applied to the tank for the purpose of tightly closing it. The tank is shown as having a gage *c* for indicating the level of the contents thereof, and said tank may be equipped with other desired devices.
- 5 10 *C* designates a distributing pipe which is attached to the tank, preferably at the bottom portion thereof. This pipe leads or conducts the liquid soap to any desired place of use, and as shown said pipe is provided with 15 branches *c'* which are adjacent to the wash-stand *B*. It will be understood that any desired number of distributing pipes, such as *C*, may be employed in connection with the closed storage tank *A*, and further that each 20 distributing pipe may have any appropriate number of branch pipes.
- At the place where the soap is to be used, the pipe *C* or its branch *c'* is equipped with a dispensing valve *D*, one form of which is 25 shown in Fig. 3 of the drawings. Said valve consists of a sectional casing, the members or sections of which are indicated at *d d'*. The member *d'* is coupled detachably to the member *d* by a threaded joint *e*, and 30 said member *d'* is provided with a chamber *f* and with a passage *f'*. A delivery nozzle or cap *E* is screwed or otherwise coupled to the lower end of the member *d'* and this cap is provided with a contracted orifice or outlet *e'*. A partition *F* is secured in the member *d'* of the valve casing above the delivery nozzle or cap *E*, and said partition is shown as having a central opening in which is adapted to operate a conical pointed valve 35 *G*, the latter being movable through the partition and toward the orifice *e'* of the delivery cap. The valve *G* is at the lower end of a rod *H*, the latter extending through the valve casing. A portion of this rod is provided with a pressure piece or head *h*, and 40 said rod works in a stuffing box which contains a packing *g* that is adapted to be compressed by the adjustment of the gland *g'*. The rod *H* carries a piston *I*, the latter being 45 fixed to or made in one piece with said rod, so as to work in the chamber *f* of the valve casing. The external diameter of the piston *I* corresponds substantially to the internal diameter of the passage *f'* in order 50 that said piston may work in the passage in a way to eject a predetermined quantity of liquid soap from the dispensing valve on the depression of the rod *H*. The piston is shown as having an enlarged flange *i* which 55 is adapted to engage with a shoulder of the valve-casing-member *d'* for the purpose of limiting the downward movement of said piston and the rod. A perforated plate or diaphragm *J* is clamped between the upper 60 end portion of the member *d'* and shoulder 65

of the member *d*, and to secure a tight joint between the parts *d d'* of the casing, a packing or gasket *j* is arranged between said partition *J* and the aforesaid shoulder of the casing member *d*. The partition *J* serves as 70 a guide to the rod *H* which passes loosely through one of the perforations in said partition.

K designates a spring which fits loosely around the rod *H* between the valve *G* and 75 the piston *I*, said spring tending to normally lift the rod to the position shown in Fig. 3. The member *d* of the casing is coupled to the distributing pipe *C* or one of its branches, and this casing of the valve is 80 filled with liquid soap above the valve *G* and partition *F* in which said valve is adapted to operate. The spring *K* acts to lift the rod *H* so that the piston *I* is in a raised position, and the valve *G* occupies or fills the 85 opening in the partition *F*, whereby the valve *G* is closed to cut off the escape of liquid soap from the dispensing valve, and to prevent the admission of air to the distributing pipe and the storage tank of the 90 soap dispensing system.

For the purpose of controlling the quantity of soap which flows from the tank to the dispensing valve, and for shutting off the flow of soap from the tank to any of the dispensing valves, I employ throttle valves in the pipe *C* or its branches *c'*. One of said throttle valves is shown in detail in Fig. 5, and in Figs. 1 and 4 the pipe *C* and its branches *c'* are each shown as having one of 95 said valves *L*. The throttle valve consists of a body *m* and a plug *n*, said body being secured to or within the pipe *C* or its branch *c'*. Said body is shown as having a central bore or passage *m'*, the diameter of which is 100 quite small as compared with that of the distributing pipe or its branch, and said body is, furthermore, provided with a passage at right angles to the bore *m'*, which passage affords a seat for the plug *n*. The plug is 105 fitted in the body at right angles thereto, and said plug has a passage *o* which is adapted to be brought into alignment with the bore *m'*. The plug is provided with an exposed key member *p* to which a wrench or 110 key may be applied for the purpose of turning the plug and thereby bringing its passage *o*, more or less into registration with the bore *m'* of the body, whereby the plug may be adjusted to cut off the passage of liquid 115 soap through the throttle valve, or it may regulate the quantity of soap which passes through the throttle to the dispensing valve *D*.

After the apparatus is installed the tank 120 *A* is filled with liquid soap and the closure *b* is applied for securely closing said tank. The dispensing valves are closed by the springs *K* thereof and the liquid soap fills the pipe *C*, its branches *c'* and the valves 125 130

D above the partitions F thereof. It will be observed that the liquid soap is stored in the tank, the distributing pipe and the dispensing valves, entirely free from contact with the external air, thus preventing loss by evaporation of the essential oils and volatile elements of the soap. When it is desired to use the soap, the operator presses on the exposed head h of the rod, thereby depressing the said rod so as to open the valve G and force the piston I downwardly, said piston acting on the soap contained in the passage f' so as to eject a predetermined quantity of soap from the dispensing valve, 5 the soap finding a free exit through the orifice e' of the cap or nozzle E. The dispensing valve may be regulated to automatically discharge a minute quantity of liquid soap, say 1 to 2 drops each time the rod H is operated. When pressure is removed from the rod, the spring at once acts to close the valve G and lift the piston I, thus restoring the parts to their normal positions and cut off the further egress of 25 soap.

An important feature of the operation is that air is admitted by the valve to the pipe and the tank when said valve is operated to eject a predetermined quantity of soap. The successive operations of the valve in dispensing the soap acts in a well known manner to lower the level of the liquid soap in the air tight tank, and thus the air in the space within the tank, above 30 the soap level therein, would have a tendency to establish a partial vacuum therein were it not for the fact that the air admitted by the valve passes into said space within the tank above the soap level therein. 35 It is thus evident that the act of dispensing the soap tends to create a partial vacuum, or rarefaction of air, within the tank, and the forceful ejection of soap by the pump-like action of the piston valve, admits air 40 to the line of pipe connecting the valve with said tank. Now, the air which may be contained in the dispensing valve above the piston therein, or be present in the pipe line, will to a certain extent have a tendency to 45 be drawn upwardly through the liquid soap present in the pipe by the suction due to the presence of the partial vacuum or the rarefaction of air within the tank, as a result of which the air admitted by the operations of 50 the dispensing valve will pass the throttle valve notwithstanding the restricted liquid and air passages therein. Obviously, the bore or passage m' in the throttle valve may be of such dimensions and be so formed by 55 a skilled mechanic that the liquid soap will flow in one direction so as to pass out of the throttle and dispensing valves whereas air will pass or "bubble" in an opposite direction 60 through the pipe line and the throttle valve so as to enter the air tight tank for

the purpose of admitting the necessary volume of air to said tank for replacing the liquid soap displaced therefrom, thereby precluding the atmospheric pressure from balancing the liquid and stopping the out-flow of soap. 70

From the foregoing it is apparent that two forces act to induce the flow of air through the liquid column present within the pipe line; first, the air admitted by the dispensing valve has a tendency to rise through the soap, and, second, the partial vacuum established in the tank above the soap level tends to draw the air from the soap column into the space above the tank, 75 it being apparent that the dispensing valve operates with a piston-like action to forcibly eject the soap. Thus, with the continued operation of the valve, the air will find its way past the throttle. The air thus admitted to the tank is brought into intimate contact with the descending column of soap, thereby thoroughly aerating the same, which air is a very important factor 80 in causing the soap to rapidly lather. 85

Having thus fully described the invention, what I claim as new, and desire to secure by Letters Patent is:

1. In an apparatus for storing and dispensing liquid soap, a tank or container closed against the admission of external air and wherein liquid soap is adapted to be contained without exposure to the external air for the purpose of precluding congelation of the soap and loss of the essential oils and perfumes thereof by evaporation, a manually operated valve in communication with said tank or container, said valve operating to dispense a predetermined quantity of soap and to simultaneously admit a like quantity of air to the tank or container, whereby the soap in the tank is aerated by the air passing upwardly therethrough and the air thus admitted is free to accumulate 100 in the tank or container above the level of the liquid soap therein, and means for closing said valve automatically upon the cessation of the outflow of soap and the inflow of air through the valve. 105

2. In an apparatus for storing and dispensing liquid soap, a tank or container closed against the admission of external air and wherein liquid soap is adapted to be contained without exposure to the external air for the purpose of precluding congelation of the soap and loss of the essential oils and perfumes thereof by evaporation, a distributing pipe connected to said tank, a manually operated valve co-operating with 110 said pipe and adapted to be supplied thereby with liquid soap from the tank or container, said valve operating to dispense a predetermined quantity of soap and to simultaneously admit a similar volume of air 115 to the pipe and to the tank or container, 120

125

130

whereby liquid soap in the pipe and tank is aerated by the air passing through the soap, and the liquid soap thus discharged from the tank is replaced by air to preclude 5 the formation of a vacuum in the tank, and means for closing said valve automatically upon the cessation of the outflow of soap and the inflow of air.

3. In an apparatus for dispensing liquid 10 soap, the combination of a tank closed against the admission of external air for precluding the evaporation and contamination of the ingredients of liquid soap which is stored in said tank under the pressure of 15 air admitted thereto by the operation of a dispensing valve, a distributing pipe connected to the bottom of the tank and adapted to be supplied with liquid soap by gravity therefrom, and a spring pressed dispensing 20 valve communicating with said pipe, said valve operating to eject a predetermined limited quantity of liquid soap and to simultaneously admit sufficient air to the pipe and the tank to compensate for the 25 discharge of liquid soap therefrom.

4. In an apparatus for dispensing liquid soap, a closed tank for the storage of liquid soap free from contact with external air, a distributing pipe, a dispensing and regulating 30 valve of the push piston type connected to said pipe for discharging a predetermined quantity of liquid soap and simultaneously admitting a small volume of air to the tank, means for automatically closing 35 said dispensing valve, and a throttle intermediate of the tank and said valve for shutting off the supply of liquid soap to said valve.

5. In an apparatus for dispensing liquid 40 soap, the combination of a closed tank wherein liquid soap is stored free from contact with external air, the liquid soap in said tank being exposed to the pressure of air admitted to the tank by the operation of 45 a dispensing valve, a distributing pipe provided with a plurality of branches, a liquid

dispensing and air admitting valve of the push piston type positioned on each of said branches, each valve having a spring for automatically closing the same, and throttles 5 in the respective branches of the distributing pipe.

6. In an apparatus for dispensing liquid soap, an air tight tank wherein liquid soap is adapted to be stored free from exposure to 5 the external air, whereby the soap is retained in a condition to preclude congelation and the loss of essential oils, a push-piston valve, means for connecting said valve to the tank, and means for impelling 6 the piston element of said valve normally to a seat for cutting off the flow of liquid there-through, said valve embodying means whereby a predetermined quantity of liquid soap is discharged, and a limited volume of air 61 is admitted to the tank, upon each operation of said valve, the air thus admitted by the valve bubbling through the soap present in the tank for the purpose of aerating the liquid soap. 7

7. In an apparatus for dispensing liquid soap, a closed tank for the storage of liquid soap free from contact with external air, a distributing pipe connected to said tank, a manually-operated valve on said pipe, 71 means for admitting air through said valve each time a predetermined quantity of soap is delivered by said valve, means whereby a restricted passage is produced in the distributing pipe at a point intermediate the 8 tank and the dispensing valve, and a throttle valve operable to vary the area of said restricted passage, said throttle valve being independent of the dispensing valve.

In testimony whereof I have signed my 81 name to this specification in the presence of two subscribing witnesses.
